 a corporation of Ohio

Application June 7, 1944, Serial No. 539,132

3 Claims. (Cl. 299—147)

The invention relates generally to hose nozzles, and more particularly to nozzles used on fire hose for producing a straight stream and spray, either singly or in combination, and the present application is a continuation in part of our copending application, Serial No. 503,208, filed September 21, 1943.

Certain prior nozzles, adapted for producing a straight stream and a spray, have been required by their design and construction to produce a hollow cylindrical straight stream either with or without a concentric spray or mist. Such hollow stream is satisfactory for fighting small fires but does not have sufficient volume for fighting larger fires where a large volume of water is required continuously to extinguish or control the flames.

Other combination spray and stream nozzle constructions have been proposed in which the straight stream is solid, but the breaking up of particles of water to produce a fine spray or mist has been limited by the fact that as the spray outlet is constricted it quickly becomes clogged with the dirt and debris in the average water supply. It has been proven in fire fighting practice that the finer the spray produced so as to most nearly approach a vapor, the more effective it is in extinguishing fires by smothering or blanketing the same.

Accordingly, the continuous production of a fine mist or vapor is important if not essential, especially when fighting certain types of fires such as oil and electrical fires which must be smothered or enveloped with mist or vapor in order to be extinguished.

It is also very important to provide for producing a continuous fine mist or vapor while subjecting the nozzle to rough or abusive use such as usually occurs as the hose and nozzle thereon is thrown or knocked about against pavements and buildings in fire fighting emergencies. Accordingly, the adjusting parts for producing and controlling the spray must be maintained in accurate alignment.

It is therefore an object of the present invention to provide a novel and improved nozzle which overcomes the foregoing disadvantages of prior constructions.

More specifically, it is an object to provide an improved nozzle which will provide either a solid straight stream alone or in combination with a very fine mist or vapor, or the mist or vapor alone, or complete shut-off.

Another object is to provide an improved combination nozzle which is adapted to produce continuously a very fine mist or vapor from an av-

erage or ordinary water supply containing foreign matter, without substantial clogging.

A further object is to provide an improved combination nozzle in which the adjusting parts for producing the spray are maintained in accurate alignment.

Another object is to provide means at the spray outlet for breaking up the water particles, without interfering with the spray shut-off.

A still further object is to provide a simple, compact and inexpensive construction which embodies all of the foregoing objectives.

It is another object of the invention to provide a nozzle which is adapted to produce an outwardly directed fog at substantially right angles to the axis of the nozzle to form a protective shield and to simultaneously produce inwardly directed streams at approximately an angle of 45° to the axis of the nozzle and arranged to impinge upon one another to produce a fog or mist.

A further object is to provide a nozzle of this character in which the barrel of the nozzle is tapered on a radius terminating at the head of the barrel adjacent to the angular opening therein which produce the inwardly directed, impinging streams.

These and other objects are attained in the present invention which is shown by way of example in the accompanying drawings, and hereinafter described and claimed.

In general terms the present improved nozzle includes an inner barrel having a central bore with a ball type shut-off at one end, and an outer sleeve providing an annular spray outlet around the other end of the barrel, said sleeve being adjustable to regulate the spray and to close off the supply thereto within said sleeve.

Referring to the drawings showing a preferred embodiment of the invention;

Fig. 1 is a longitudinal sectional view of the improved nozzle with the parts in position to produce a spray or mist alone;

Fig. 2 a similar view with the parts in position to produce a solid straight stream alone;

Fig. 3 a similar view partly in elevation and partly in section on a plane at 90° from the plane of Fig. 2;

Fig. 4 a transverse sectional view as on line 4—4, Fig. 3;

Fig. 5 a transverse sectional view as on line 5—5, Fig. 2;

Fig. 6 a transverse sectional view as on line 6—6, Fig. 2;

Fig. 7 is a longitudinal sectional view of a mod-

ified form of the improved nozzle in which the spray or mist produced is in the form of an outwardly directed protective shield and a plurality of angular, inwardly directed, impinging streams, with the parts in position to produce a spray or mist alone;

Fig. 8 is a similar view of the forward end portion of the nozzle shown in Fig. 7, with the parts in position to produce a solid, straight stream alone;

Fig. 9 is a view similar to Fig. 8 showing the nozzle producing both a solid, straight stream and a protective shield or fog, and

Fig. 10 is a transverse sectional view as on the line 10—10, Fig. 7.

Similar numerals refer to similar parts throughout the drawings.

Referring first to Figures 1 to 6 inclusive, the improved nozzle preferably includes a housing 7 which is generally tubular in shape and which is provided at one end with the usual female screw threads 8 for attachment to a standard hose coupling part provided on the end of the fire hose on which the nozzle is to be used. The opposite end of the housing 7 encircles the inner end of a barrel 9 which has a central cylindrical bore 10 adapted for discharging water in a solid straight stream, as indicated at 11 in Fig. 2.

The outer end of the barrel 9 projects beyond the housing 7 and is surrounded by a sleeve 12 which is longitudinally adjustable with respect to the barrel 9. Preferably the barrel 9 is provided intermediate its ends with an annular extension 13, and the sleeve 12 is screwed on the forward portion of said annular extension, as indicated at 14 so that the longitudinal adjustment of the sleeve is obtained by screwing the same in either direction on the barrel. Means for limiting the longitudinal movement of the sleeve may constitute a pair of set screws 15 in the sleeve wall, which set screws abut the annular extension 13 for limiting movement of the sleeve toward the housing 7 and abut a conical rib 16 on the barrel 9 for limiting movement of the sleeve in the other direction. Preferably, an annular gasket 17 is provided between the sleeve 12 and annular extension 13 for preventing leakage between these two members.

Preferably, the front end of the housing 7 is screwed onto the rear end of the annular extension 13 of the barrel, as indicated at 18 to provide a rigid connection between the housing and the barrel with an annular passage 19 between the two. A gasket 20 is preferably provided at the base of the threads 18 to prevent leakage between the housing and the annular extension 13.

For providing communication between the annular passage 19 and the inner part of the sleeve 12, a circular or annular series of longitudinal ports or holes 21 is provided in the annular extension 13 of the barrel. The size and spacing of the ports 21 is such that considerably more water is supplied to the sleeve than is normally necessary for creating the required volume of spray at the outer end of the sleeve, so that even though a relatively large number of the ports 21 become clogged, the spray discharged will still function satisfactorily.

The outer end of the sleeve 12 is preferably inwardly constructed or tapered as indicated at 22 to provide a small annular spray outlet 23 around the outer end of the barrel 9. Preferably the outer end of the barrel is provided with an external lip 24 which has a series of serrations

25 on its rear edge, so that water flowing through the sleeve and discharging from the outlet 23 will impinge the serrations and be broken up into very fine particles, producing a conical mist or vapor discharge, as indicated at 24a in Fig. 1.

Means for closing off the water supply to the spray outlet 23 preferably includes an inner conical rib 26 on the sleeve 12 which is adapted to seat on the front conical face of the conical rib 16, thus providing a shut-off for the spray outlet within the sleeve 12. Preferably a ring of composition material 27 is provided on the rib 16 for insuring a tight seat. By thus providing the closure for the spray outlet within the sleeve 12 instead of at the spray outlet, the serrations 25 may be provided at the spray outlet to break up the spray and obtain a fine mist or vapor discharge.

Means for maintaining the sleeve in accurate alignment with the barrel 9 preferably includes a ring 28 slidably engaging the barrel 9 and supported on the sleeve by spaced ribs 29. Thus, even though the nozzle is subjected to the rough usage incident to fire fighting including lateral impacts on the sleeve, the spray outlet 23 is maintained accurately annular at all times to prevent clogging at one side or the other.

Preferably the housing is provided with a ball-type shut-off for controlling water flowing through the barrel 9. The shut-off 30 is provided with a cylindrical passage 31 of the same diameter as the bore 10 and adapted to be aligned therewith. As shown, the ball shut-off may have at one side a segmental seating member 32 for seating in the end of the barrel 9, as indicated in Fig. 1, when the ball is turned to shut-off position. Preferably the member 32 is provided with an inwardly projecting boss 33 slidably received in a hole 34 communicating with the passages 31, and the member 32 is preferably cushioned on the ball by means of a gasket 35 or the like. Thus in closed position the pressure of the water is exerted against the inner side of the member 32 to provide a tight seat against the end of the barrel 9. Preferably, a spherically shaped rib 36 is provided in the housing 7 for engaging the member 32 and maintaining the ball in alignment when it is in open position as shown in Fig. 2.

The ball shut-off 30 is preferably journaled in the housing 7 as shown in Fig. 3 by providing diametrically opposite studs 37 and 39 on the ball journaled in the housing walls. Preferably the stud 38 is extended through the housing wall as indicated at 39 for connection with a usual shut-off handle yoke 40 which is also journaled on a boss 41 provided on the opposite side of the housing. A suitable packing gland 42 is provided around the stud extension 39, and the housing wall around said extension may be in the form of a removable plate 43 for giving access to the ball shut-off.

Means for straining the water flowing around the ball to the spray outlet passages 21 preferably includes a frusto-conical perforate strainer 44 secured in the housing 7 between the screw threads 8 and the ball shut-off. The strainer 44 is of relatively fine mesh so as to catch a sufficient proportion of dirt, sea weed, gravel and the like which may be present in the water supply. Due to the conical shape of the strainer with its smaller open end adjacent the passage 31 in the ball shut-off, even though the strainer becomes clogged with foreign material, the same may be thoroughly cleaned out and flushed by merely turning the ball shut-off to the open posi-

tion of Figs. 2 and 3. Moreover, in the case of any foreign material getting past the strainer 44 the circular series of ports 21 acts as a secondary screen, and it should be noted that the amount of water normally flowing through the strainer 44 and ports 21 is of such capacity that even though both the strainer and the ports are partially clogged sufficient water will reach the spray outlet 23 to produce a mist or vapor discharge of required volume.

In the operation of the improved nozzle, when the shut-off is in the position of Fig. 1, water flowing into the housing 7 will pass through the strainer 44 and around the ball to the ports 21. With the sleeve 12 in the position of Fig. 1 water will flow in the direction of the arrows past the seat 27 between the ribs 16 and 26 and out through the spray outlet 23 in the form of fine conical mist 24. In order to obtain a complete shut-off with the ball 30 in closed position, it is only necessary to screw the sleeve 12 rearwardly on the barrel 9 until the inner rib 26 of the sleeve seats on the rib 16 of the barrel.

With the ball shut-off 30 in the position of Figs. 2 and 3 a solid straight stream 11 is discharged from the front end of the barrel, and by manipulating the sleeve 12 the conical mist 24 may or may not be produced as desired. Thus, the nozzle provides four ways or positions for producing namely, a solid straight stream alone, 30 a spray or mist alone, a combination of straight stream and mist, and a complete shut-off.

In Figs. 7 to 10 inclusive, a slightly modified form of the improved nozzle is shown in which the generally tubular housing 7a is internally threaded at one end, as at 8a, for attachment to a standard hose coupling, the opposite end of the housing encircling the inner end of the barrel 9a which has the central cylindrical bore 10a adapted for discharging water in a solid straight stream as indicated at 11a in Figs. 8 and 9.

The outer end of the barrel 9a projects beyond the housing and is surrounded by the sleeve 12a which may be screwed upon the forward portion of the annular extension 13a of the barrel, as indicated at 14a, whereby longitudinal adjustment of the sleeve may be obtained by screwing the same in either direction on the barrel.

The means for limiting the longitudinal movement of the sleeve preferably includes a helical spring 15a in ring form which is held by its own resiliency in an annular groove 16a in the barrel 9. The spring forms a cushion stop by abutting the ribs 29a when the sleeve 12a is moved to the positions of Figs. 7 and 9 for producing a mist or fog. Obviously, the axis of the spring 15a must be inward of the outer edge of the groove 16a to prevent dislodging the spring. The annular gasket 17a may be provided between the sleeve 12a and the annular extension 13a to prevent leakage between these members.

The forward end of the housing 7a may be screwed upon the rear end of the annular extension 13a as indicated at 18a to provide a rigid connection between the housing and the barrel with an annular passage 19a between the two, and a gasket 20a may be provided at the base of the threads 18a to prevent leakage at this point.

Communication may be provided between the annular passage 19a and the inner end of the sleeve 12a through an annular series of longitudinal ports 21a formed in the annular extension 13a of the barrel.

The outer end of the sleeve 12a is provided with

the internal annular flange piece 22a, which is preferably screwed into the barrel as shown. The inner circumference of the piece 22a is slightly larger than the forward portion of the barrel 9a, and the forward surface of the piece 22a is very slightly inclined as at 23a and terminates adjacent to the external lip 24b at the outer end of the barrel.

The outer surface portion of the barrel 9a is reduced, being longitudinally curved on a radius as indicated at 25a extending from a point slightly in rear of the flange 22a of the sleeve in its closed position of Fig. 8 and terminating in a cylindrical portion at the external lip 24b where it is provided with a plurality of ports 25b located at substantially 45° to the axis of the barrel.

As best shown in Fig. 8, the inner circumferential surface of the flange piece 22a is preferably provided with serrations 22b inclined in one direction from the axis of the nozzle, and the outer circumferential surface of the lip 24b is provided with serrations 24c inclined in the opposite direction. As shown the serrations 24c are much finer than the serrations 22b, the serrations in both cases being rolled at an angle of about 5° to 10° with the axis of the barrel, and the serrations 22b are preferably about 21 pitch (21 to the inch) while the serrations 24c are preferably about 33 pitch.

We have found that the use of oppositely inclined serrations produces an exceptionally fine mist or vapor, and that the use of a finely serrated lip with a coarser serrated sleeve outlet acts to further break up the particles of water and cause the finer particles to migrate toward the center, thus producing a very dense vapor.

With the parts in the position shown in Fig. 7, for producing a mist or spray, a protective shield will be discharged at substantially right angles to the axis of the nozzle along inclined surface 23a, as indicated at S, while impinging streams 45 will be discharged inward through the ports 25b producing a fog or mist at the axis of the nozzle. The impinging streams should not be less than at a 45° angle to the nozzle axis although they may be somewhat greater, being shown at about 45° which is the ideal angle, because the resulting spray then has sufficient forward motion, without having too much, in which latter case the impingement does not break up the spray sufficiently.

The point A at the rear of the internal annular flange 22a of the sleeve should at all times be ahead of the point B where the curve 25a begins as otherwise the water tends to follow the axial line of the barrel. The curve 25a is provided in order to get a sweep of water and form a dense protective shield of fog which is deflected by lip 24b at substantially right angles to the axis of the nozzle, the water being deflected from the surface 25a and behind external lip 24b and directed outward across the slightly inclined forward surface 23a in a substantially right angular mist or spray. If the barrel were reduced or tapered on a straight line instead of a curve the angle of deflection tends to shoot the water out at about a 45° angle.

The means for closing off the water supply to the spray outlet includes the inner conical rib 26a on the sleeve which is adapted to seat on the rib 16b on the barrel. A ring or composition material 27a may be provided on the rib 16b for insuring a tight seat.

The sleeve may be maintained in accurate alignment with the barrel by means of a ring

28a slidably engaging the barrel and supported on the sleeve by the spaced ribs 29a. The housing may be provided with a ball type shut-off 30a, similar to that shown in Figs. 1 to 3 inclusive, for controlling water flowing through the barrel. A cylindrical passage 31a, of the same diameter as the bore 18a and adapted to be aligned therewith, is provided in the shut-off 30a. A segmental seating member 32a may be provided at one side of the ball shut-off for seating in the end of the barrel in the manner above described when the ball is turned to shut-off position. This segmental member has the boss 33a slidably received in the hole 34a communicating with the passage 31a and is preferably cushioned on the ball by means of the gasket 35a.

A frusto-conical strainer 44a may be secured to the housing 7a between the threads 8a and the ball shut-off for straining the water flowing around the ball to the spray outlet passages in the manner above described.

The nozzle produces a fine mist or vapor continuously despite abusive use because of its rugged construction, because positive means is provided for maintaining alignment of the sleeve around the barrel and because water supplied to the spray outlet is effectively strained while passing through the nozzle.

We claim:

1. Nozzle construction including a hollow barrel open at both ends and having an exterior annular extension intermediate its ends provided with a circular series of holes extending longitudinally therethrough, a housing screwed on the inner end of said annular extension, a shut-off swiveled in said housing and adapted for closing the inner open end of said barrel, a sleeve adjustably secured on the outer end of said annular extension for longitudinal movement relative to the barrel and providing an annular spray outlet around the outer end of the barrel, cooperating means on said barrel and sleeve for providing a spray closure spaced from said spray outlet and within said sleeve; and means ex- 45

tending radially inward from said sleeve intermediate its ends slidably engaging said barrel for maintaining alignment between said sleeve and barrel.

5. 2. Nozzle construction including a hollow barrel open at both ends and having an exterior annular extension intermediate its ends provided with a circular series of holes extending longitudinally therethrough, a housing screwed on the inner end of said annular extension, a shut-off swiveled in said housing and adapted for closing the inner open end of said barrel, a sleeve adjustably secured on the outer end of said annular extension for longitudinal movement relative to the barrel and providing an annular spray outlet around the outer end of the barrel, and means extending radially inward from said sleeve intermediate its ends slidably engaging said barrel for maintaining alignment between said sleeve and barrel.

10. 3. Nozzle construction including a hollow barrel open at both ends and having an exterior annular extension intermediate its ends provided with a circular series of holes extending longitudinally therethrough, a housing screwed on the inner end of said annular extension, a shut-off swiveled in said housing and adapted for closing the inner open end of said barrel, a sleeve adjustably secured on the outer end of said annular extension for longitudinal movement relative to the barrel and providing an annular spray outlet around the outer end of the barrel, the outer end of said barrel having an exterior annular serrated lip for breaking up spray particles, cooperating means on said barrel and sleeve for providing a spray closure spaced from said spray outlet and within said sleeve, and means extending radially inward from said sleeve intermediate its ends slidably engaging said barrel for maintaining alignment between said sleeve and barrel.

JOHN C. SCHELLIN.
EARL J. HOUSEKEEPER.
WILLIAM H. BRUBAKER.
